CLAIM

The ornamental design for a door hinge, as shown and described.

DESCRIPTION

FIG. 1: is a perspective view of the door hinge, shown reduced in scale and in an environment of use, the broken lines forming no part of the claim;

FIG. 2: is a perspective view of FIG. 1;

FIG. 3: top view thereof;

FIG. 4: is a right side view, thereof;

FIG. 5: is a left side view, thereof; and,

FIG. 6 is a bottom view, thereof.

The door and door frame, enclosed by dotted lines in FIG. 1, are excluded. Only the external portions of the ornamental hinge (FIG. 1, 101) are included.

1 Claim, 5 Drawing Sheets
